UNITED STATES PATENT OFFICE.

ARTHUR W. COX, OF BALLARD VALE, MASSACHUSETTS.

DESIGN FOR A KNIFE-HANDLE.

SPECIFICATION forming part of Design No. 16,781, dated July 6, 1886.

Application filed May 22, 1886. Serial No. 203,048. Term of patent 14 years.

To all whom it may concern:

Be it known that I, ARTHUR W. COX, a citizen of the United States, residing at Ballard Vale, in the county of Essex and State of Massachusetts, have invented and produced a new and original Design for Knife-Handles; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

Figure 1 is a plan view of my newly-designed knife. Fig. 2 is an edge view of the same.

The leading feature of my design consists in a handle for table-cutlery expanded laterally on each side of the blade, and extending therefrom at a point about midway between its edges, forming a long narrow neck portion, which, at a distance from the blade curving symmetrically outward in opposite directions in the plane of the blade and back toward each other, forms points and terminates in an expanded and curved end, as clearly shown in the plan view of Fig. 1. The double-edge blade A is provided with the handle B, pro-

jecting therefrom about midway between its edges. The handle comprises the long neck portion b and the rounded and expanded end b'. At the inner end the neck b is expanded laterally on each side of the blade into rests b². The opposite end, curving outwardly and inwardly symmetrically in opposite directions in the plane of the blade, forms the projections b³ and the contracted portion b⁴. The inward curves are again deflected and gradually recede and approach, and, uniting, form the expanded and curved end b'.

I claim—

A design for handle for knives or kindred article of table-ware herein shown and described, the same consisting of a handle having the narrow neck, expanded laterally at one end, on each side of the plane of the blades, and curving outward and inward, at the other end forming points which extend in the plane of the blade, the expanded end, and the contracted portion between the points and expanded end.

In testimony whereof I affix my signature in presence of two witnesses.

ARTHUR W. COX.
